Specification for Design.

Patented Feb. 7, 1922.

Application filed February 28, 1921. Serial No. 448,601. Term of patent 14 years.

To all whom it may concern:

Be it known that I, GARRETT LAYTON GRIER, a citizen of the United States of America, residing at Milford, in the county of Sussex and State of Delaware, have invented a new, original, and ornamental Design for a Tray for Holding Dental Instruments and Supplies, of which the following is a specification, reference being had to the accompanying drawing, in which—

Figure 1 is a perspective view, and Figure 2 is a longitudinal sectional view of a tray for holding dental instruments and supplies, showing my new design.

I claim:

The ornamental design for a tray for holding dental instruments and supplies, as shown.

G. LAYTON GRIER.
